TURBINE BLADE

Paul Faber, Baden, Switzerland, assignor to Aktiengesellschaft Brown, Boveri & Cie, Baden, Switzerland

Application July 21, 1939, Serial No. 285,822
In Germany July 27, 1938

7 Claims. (Cl. 60—41)

This invention relates to turbine blades and particularly to gas turbine blades of the type in which a stream of a cooling fluid, such as cool air, flows over the surface of the blade as a protection against overheating by the hot gases.

Hollow blades with outlet openings along the center of the leading edge of the blade have been used but this location of the outlet opening or slit has the disadvantage that the slit may be clogged by dust, cinders or other foreign matter in the high temperature gas. According to another prior design, the outlet slit or slits have been at the sides of a hollow blade, but the thin blades and blade parts were eroded in a short time by the unavoidable impurities in the gas.

An object of the present invention is to provide gas turbine blades having a main section and a leading edge or fore section to which a cooling fluid is supplied, the passage for the cooling fluid and the openings for discharging the fluid at the blade surface being in the fore section or, alternatively, between the main and fore section of the blade. An object is to provide a blade having a main section and a fore section that is of harder metal than the main section, there being an air passage and outlet slits in the fore section or between the fore section and the main section. An object is to provide a turbine blade having a main section and a fore section, of crescent shape in cross-section, that serves as the leading edge of the blade and is spaced from the main section to form an air passage and outlet slits between the main section and the fore section.

These and other objects and advantages of the invention will be apparent from the following specification when taken with the accompanying drawing in which:

Fig. 1 is a transverse section through a turbine blade embodying the invention;

Figs. 2, 3 and 4 are fragmentary elevational views, with parts in section, of different forms of multi-part blades and mountings therefor;

Fig. 5 is a transverse section through another form of blade;

Fig. 6 is a transverse section through the root of the fore section of the blade shown in Fig. 5; and

Fig. 7 is a transverse section through another embodiment in which the air passage is formed, in part, by a longitudinal groove in the main section of the blade.

As shown in Figs. 1 to 4, the turbine blade is formed by a solid main section 1 and a fore section 2 that is of approximately crescent shape

that constitutes the leading edge of the blade. The curvatures of the adjacent longitudinal surfaces of the two blade sections are such that a passage 3 is formed between the sections and outlet slits 4 are provided along each side of the blade.

Cooling fluid that is supplied to the passage 3 will flow out through the slits 4, as indicated by the lines a, to protect the main section of the blade from the hot gas that travels along the path indicated by the broken lines b. The main section may be formed from the materials customarily employed but the fore section 2 is preferably formed of a particularly hard metal, such as "Stellite," chrome-nickel-tungsten steel or the like that can resist erosion by the dust and cinders in the gas. The composite blade may be either a moving blade or a stationary guide blade.

The main section 1 is provided with the usual pressed or milled projecting base 5 for engagement by the flanged parts 6 that mount the blades in the undercut groove of a blade carrier 7. The fore section 2 must be mounted in such manner that the cooling fluid may be supplied to the passage 3 in the blade from a channel 8 in the blade carrier. As shown in Fig. 2, the fore section 2 is of the same cross-section throughout its length and is coextensive with the main section 1 and its mounting flange 5. Section 2 is secured to the main section 1 by longitudinal welds 9 that close the slits 4 at the part of the blade that lies within the blade groove, and by weld metal 10 that forms an extension of the cover 11 that is welded across the outer end of the passage 3.

As shown in Fig. 3, the fore section 2' is provided with an end flange 12 which is engaged by the flanged parts 6 that lie between adjacent blades. The construction in other respects is like that shown in Fig. 2. As shown in Fig. 4, the base flanges may be omitted from both the main section 1' and the fore section 2' of the blade, and each section secured to the mounting pieces 6 by weld metal 13.

The air passage and outlet slits may be formed entirely within the fore section 2a, Fig. 5, that has outer and inner curved walls 14, 15 that are joined by a longitudinal rib 16. The rib 16 terminates at the ring groove of the blade carrier and the inner end of the fore section is tubular, see Fig. 6. The section 2a is well cooled by the air flow and by the transfer of heat through rib 16 and the inner wall 15 to the main section 1 of the blade. The inner surface of the wall por-

tion 15 conforms to the outer surface of the main section 1 and the parts may be brazed or welded to each other.

When air passages of large size are required, 5 the wall thickness of the fore section 2 may be reduced, Fig. 7, and a longitudinal groove 17 formed in the forward edge of the main section 1a. This construction has the advantage of 10 low cost as the erosion-resistant metal of the fore section is quite expensive and it would not be economical to enlarge the fore section to provide a large air passage.

It is to be understood that the invention is not restricted to the particular constructions herein 15 shown and described as changes may be made in the design, shape and relation of the parts without departing from the spirit of my invention as set forth in the following claims.

I claim:

20 1. In a turbine blade construction for high temperature gas turbines, a blade comprising a main section and a fore section in advance of the main section and constituting the leading edge of the blade, a blade carrier having a groove for receiving blades and a channel for cooling fluid opening into said groove, a passage extending longitudinally of said fore section and open through a longitudinal slit to one side of the blade, means mounting the inner ends of said 25 blade sections in the groove of said blade carrier with the passage of said fore section in direct communication with the channel of said blade carrier.

2. In a turbine blade construction, the invention as claimed in claim 1, wherein said fore section is of an erosion-resisting metal.

3. In a turbine blade construction, a blade comprising a solid main section and a fore section of approximately crescent shape in transverse cross-section, means securing said sections to and spaced from each other to provide a lon-

gitudinal slot along each side of the blade and a longitudinal passage between the blade sections, and means closing the outer end of said passage, whereby a flow of cooling fluid may be established along the surface of the main section of the blade 5 when said blade is mounted on a blade carrier having a channel therein for supplying cooling fluid to the blade passage.

4. In a turbine blade construction, the invention as claimed in claim 3, wherein said securing 10 means comprises weld metal filling said slots at that portion of the blade which is to be seated within the blade groove of a blade carrier.

5. In a turbine blade construction, the invention as claimed in claim 3, wherein said securing 15 means comprises mounting parts mechanically secured to the inner ends of said blade sections at the outer circumference thereof, said mounting parts serving to secure the blade to a blade carrier.

6. In a turbine blade construction, the invention as claimed in claim 3 wherein the forward edge of the main section of the blade is longitudinally grooved.

7. A turbine blade comprising a main section 25 and a hollow fore section, said fore section having an inner and an outer curved wall whose longitudinal edges are spaced apart to form a longitudinal slot at each side of the blade, a rib extending longitudinally of and joining said walls, 30 and cover means joining the outer ends of said walls, the inner surface of the inner wall conforming to and secured to the forward surface of the main section of the blade, and the inner end of the fore section being tubular and open to the 35 spaces between the inner and outer walls at opposite sides of the longitudinal rib for supplying cooling fluid to said spaces for discharge through said longitudinal slots.
